UNITED STATES PATENT OFFICE.

ROBERT M. LAMP, OF MADISON, WISCONSIN.

CRUTCH.

SPECIFICATION forming part of Letters Patent No. 467,468, dated January 19, 1892.

Application filed May 16, 1891. Serial No. 392,955. (No model.)

To all whom it may concern:

Be it known that I, ROBERT M. LAMP, a citizen of the United States, residing at Madison, in the county of Dane and State of Wisconsin, have invented certain new and useful Improvements in Appliances for Crutches, of which the following is a specification.

My invention relates to improvements in appliances for the base of crutches; and the objects of my improvements are to provide for easily and effectually regulating at will the length of the projection of the spiked peg through the buffer or other terminal, thereby graduating the proportion of the bearing weight upon the spiked peg and terminal, respectively, whereby the crutch will be adapted to all the different characters of tracks traversed by the wearer and to the use of different wearers, and to provide for the wear of the parts and for securely retaining the rubber buffer in its socket and giving to all the parts of the device solid vertical and lateral bearings. I attain these objects by the mechanism illustrated in the accompanying drawings, in which—

Figure 1 is a plan view; Fig. 2, a vertical section on the line A B, Fig. 1; Fig. 3, a bottom view; Fig. 4, a side elevation, partly broken away and in section; Fig. 5, a horizontal section on the line 1 2, Fig. 2; Fig. 6, a vertical section through line 5 6, Fig. 7, with the bolt *c* removed, showing the sleeve; and Fig. 7 a horizontal section through the line 3 4, Fig. 6, also showing the sleeve.

A standard forms all the stationary metallic parts of my device comprising the wood-socket and the buffer-socket cases, which are at the extremes, and the bearings for the bolt and nut.

a designates a wood-socket case at the summit of my device, and *g* its upward opening. The socket receives in its base the wood of the crutch, which wood has a socket in which the upper end of the screw-bolt plays in vertical adjustment.

d designates an annular socket-case at the base of the standard, and *k* its downward opening. The case is tapped into a screw throughout its inner vertical surface. The rubber buffer will be screwed into the socket to the summit of the latter, the rubber yielding to the screw-thread. If the buffer is carried by a metal

holder or any form of metallic terminal device is used, the contacting metal parts will be constructed suitably therefor. The base of the 55 socket has a plane horizontal surface to fit upon a shoulder of the buffer or other device. An opening continues inward from each of said sockets to the slot for the nut hereinafter described. Such opening is formed into bearings *l*, *j*, the lower one of which *j* is polygonal, fitting the polygonal screw-bolt hereinafter described, preventing rotary and allowing vertical motion in the bolt as it traverses a nut having end bearings. 60

n designates a slot continuing from and lying between the bolt-bearings and opening laterally through the standard on two opposite sides. The slot receives the nut herein-after described, which it exceeds in horizontal 65 and equals in vertical extent, so that the nut will be readily manipulated and will have the end bearings necessary to its operation in giving the bolt its vertical motion.

c designates a steel octagonal screw-bolt, or 70 it may be of any polygonal form. It terminates at its downward end in the inverted pyramidal four-sided spike *h*. The spike may have any other number of sides or may be conical. Such bolt in its upper position extends from above the base of the wood in the upper socket to the base of the rubber buffer, and in such position is screw-threaded from its summit to the base of the nut. 75

b designates a cylindrical nut occupying 80 its described slot *n* and receiving the screw-bolt *c*. *ii* designates a series of corrugations upon the surface of the nut for aiding in its digital manipulation, while *ff* designates holes for the temporary insertion of a lever for the 85 same purpose. The nut is inwardly annular and tapped to the screw-bolt, upon which it turns either way, thus giving the bolt reciprocal vertical motion.

e designates a cylindrical rubber buffer 90 screwed into its said socket to the extent of the latter. The lower part of the buffer is of the diameter of the socket-case, and its upper part as far as it enters the case is reduced in diameter, forming a shoulder which rests on 95 the edge of the case. The buffer has a central vertical opening to receive the screw-bolt. A metal appliance carrying the buffer or entirely taking its place may be used in my de-

vice, the contacting metal parts being properly screw-threaded to fit each other.

Another construction of a part of my device is illustrated in Figs. 6 and 7 in connection with other figures, which are applicable to both constructions.

m in Figs. 6 and 7 designates a sleeve consisting of a plate beneath the lower end of the nut *b* and a boss projecting downward centrally from the lower surface of the plate to the buffer, the slot being made large enough to receive the plate and the nut and the opening below the slot fitting the boss. The sleeve *m* has a central vertical opening through it, forming an octagonal bearing receiving and fitting the bolt *c*. The bearing and the bolt may be of any form, so that they have one plain side. A bolt cylindrical and a bearing annular, except as to a narrow plain surface on one side of each, would be a suitable construction. The sleeve will preferably be formed of a material different from that of both the bolt and nut to avoid friction and sticking in case of rust. The standard may be made of malleable iron. The sleeve is inserted by elevating the bolt and removing the nut. This construction will be comparatively inexpensive in material and labor and will admit of the replacing of the bearing for the bolt when worn and of the use of a washer when the nut or its bearings are worn. The bolt is readily adjusted vertically by properly turning the nut, and thus elevating or depressing the bolt and spike—elevating for in-

side use and soft tracks and depressing for hard, icy, or slippery tracks—and the bolt is also thus adjusted to suit all requirements of the wearer or different wearers.

Having thus described my invention, what I claim as new therein, and desire to secure by Letters Patent, is—

1. In a crutch-bottom, the combination of a standard having a slot, a polygonal bearing, a screw-socket, a nut in the slot bearing at the ends, a rubber plug in the socket, and a polygonal screw-spur through the nut, bearing, and plug, all said parts combined substantially as set forth.

2. In a crutch-bottom, the combination of a polygonal screw-spur, a nut thereon, and a frame holding the spur in a polygonal bearing and the nut in end bearings, substantially as set forth, whereby the spur may be vertically adjusted.

3. A crutch-bottom composed of a standard having a slot, a screw-socket, an intermediate opening, a sleeve in the opening having a polygonal bearing, a nut in the slot bearing on the standard and sleeve at either end, a rubber plug in the socket, and a polygonal screw-spur through the nut, bearing, and plug, all said parts combined substantially as set forth.

ROBERT M. LAMP.
